ATTORNEY

UNITED STATES PATENT OFFICE.

RALPH M. HILTON, OF NEWPORT NEWS, VIRGINIA.

HAY-PRESS.

1,332,177.

Specification of Letters Patent.

Patented Feb. 24, 1920.

Application filed February 11, 1919. Serial No. 276,338.

To all whom it may concern:

Be it known that I, RALPH M. HILTON, a citizen of the United States, residing at Newport News, in the county of Warwick 5 and State of Virginia, have invented new and useful Improvements in Hay-Presses, of which the following is a specification.

This invention relates to improvements in hay presses, operated by horsepower, and 10 the principal object of the invention is to provide means for operating the plunger in a horizontal plane, while held against any vertical or swinging movement.

Another object of the invention is to provide for a double feeding movement of the plunger for each complete revolution made by the rotatable cross head.

The invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:

30 Figure 1 is a side view of the invention.

Fig. 2 is a longitudinal section thereof.

Fig. 3 is a plan view of part of the apparatus.

Fig. 4 is an end view of the support for 35 the rotatable cross head.

Figs. 5 and 6 are detailed views.

In these views, 1 indicates the base of the apparatus. On one end of this base is supported the pressing chamber 2 and the 40 holding chamber 3. The pressing chamber is provided with the usual hopper 4 and said chamber is strengthened by the horizontal and cross strips 5. This chamber receives the plunger head 6, on the bottom of which 45 are located the rollers 7. This plunger is provided with the extension 8 for closing the hopper when the plunger is in its forward position. The chamber 2 is provided with the usual dogs 9 for holding the blocks

50 in proper position after being pushed forward by the plunger. The holding chamber is provided with the usual yieldable top 10. The plunger rod 11 is held against lateral or vertical movement by means of the guide 55 12 supported on the base and consisting of a U-shaped frame 13 carrying the rollers 14.

The stop 15 limits the rearward movement of the plunger.

An upright support 16 is located at the other end of the base, and this support consists of the upper and lower beams 17, the end beams 18 and the connecting bars 19. The upper beam of this head supports the rotatable cross head 20, which consists of a cylindrical member 21 rotatably secured 60 to the upper beam by means of the bolt 22, and provided with a flange 23, which receives the circular plate 24 on the bottom of the beam 25. The bolt 22 passes through this plate 24 and beam 25, so that all of 65 these parts are rotatably connected with the upper beam 17. The beam 25 has its ends reduced by forming recesses 26 in the under faces thereof and rollers 27 are located in these recesses. A crank member 28 is supported on the underside of the upper beam 17 by the bearings 29 and this crank member has a depending part 30 which has its lower end connected with the bar 31 by an 70 eye bolt 32, and the other end of this bar 31 75 is connected with the free end of the plunger rod 11 by the perforated strip 33 engaging the forked strip 34 connected with the end of the plunger rod 11. In this way the connection between the plunger rod 11 and the 80 bar 31 may be adjusted. The other end of the crank member 28 is provided with a curved upwardly extending member 35, which is adapted to be struck by the ends of the beam 25 when the same is rotated, so 85 as to rock the crank member to reciprocate the plunger. The rollers 27 will overcome friction between the members and prevent undue wear. A sween 36 is connected with one end of the beam 25 and this sween has 90 the usual tree 37 secured thereto. Brace rods 38 connect the upper end of the support 16 with the base and the spring 39 connects the crank member with a part of the base, so as to return the crank member 100 to its normal position with the plunger rod in its rearmost position.

It will thus be seen that the plunger is moved forwardly twice on each revolution of the beam 25. It will also be seen that 105 the guide 13 prevents any swinging or lateral movement of the plunger rod so that there is no danger of the plunger becoming jammed in the feeding chamber.

What I claim is:—

1. A hay press comprising a feeding chamber, a plunger therein, a plunger rod

connected with the plunger, an upright support, a crank member rotatably connected with said support and comprising a depending part and an upward extending member, 5 a rod connecting said depending part with the plunger rod, a spring connecting the crank member with a part of the press, a rotatable member carried by the support, a beam carried by said member and having 10 its ends adapted to strike the upwardly extending member of the crank member, and a sweep connected with said beam.

2. A hay press comprising a feeding

chamber, a plunger therein, a plunger rod connected with the plunger, a support, a 15 crank member connected with the support, means for connecting one end of the crank member with the plunger rod, an upwardly extending part on the crank member, a rotatable cross head carried by the support 20 and having a pair of projections therein for engaging the upwardly extending part of the crank member and means for rotating said cross head.

In testimony whereof I affix my signature. 25
RALPH M. HILTON.
